UNITED STATES PATENT OFFICE.

STEPHEN A. DOBYNE, OF ST. LOUIS, MISSOURI, ASSIGNOR TO CHAMPION SHOE MACHINERY COMPANY, OF ST. LOUIS, MISSOURI, A CORPORATION OF MISSOURI.

SHOE-SEWING MACHINE.

Application filed November 15, 1918. Serial No. 262,686.

To all whom it may concern:

Be it known that I, STEPHEN A. DOBYNE, a citizen of the United States, and residing at St. Louis, Missouri, have invented the 5 new and useful Improvement in Shoe-Sewing Machines, of which the following is a specification.

This invention relates to sewing machines, and more particularly to wax thread shoe 10 sewing machines, adapted for the manufacture and repair of boots and shoes.

One of the objects of this invention is to improve the heating system so as to secure sufficient heat of the mechanism for handling the wax thread.

Further objects will appear from the detail description taken in connection with the accompanying drawings, in which:

Figure 1 is a front elevation of a machine 20 embodying this invention, the front plate being cut away to show the interior construction;

Figure 2 is a side elevation from the right side of the machine; and

Figure 3 is a side elevation from the left side of the machine.

Referring to the accompanying drawings, 1 designates the machine head, which is as usual in the form of a casting, having an 20 overhanging arm 2, and attached to this overhanging arm by screws 3 is a bracket 4, the screws 3 passing through the bracket 4 and being threaded into the arm 2. A bracket section 5 is attached to the head as 30 shown at 6. Mounted in bearings in the head is a shaft 7 provided with a pulley 8, and fixed to the shaft are a series of cam wheels 9, 10 and 11, provided with cam grooves on their outer and side faces, for 35 the purpose of operating the various mechanisms. The bracket 5 is spaced from the overhanging arm 2, and the bracket 4, so as to form a table 12 for the work, and the machine head is provided with a door 13 which is movable to expose the interior of 45 the machine head.

The needle mechanism is substantially as shown and described in United States Patent No. 760,732. The needle mechanism 50 comprises a needle bar 14 carrying a needle (not shown), and this bar is reciprocated by an arm 15 on a rock shaft 16 mounted in bearings on the head and having fixed thereto an arm 17 provided with a cam

roll engaging a cam groove in the left face 55 (Figure 3) of the cam wheel 10. The needle bar is mounted on a laterally movable slide 18, reciprocated by a lever 19, interconnected with the slide and provided with a cam roll engaging a cam groove in the right 60 face (Figure 3) of the cam wheel 9. With this construction, the needle is given a feeding movement when in the work to feed the work, substantially as shown and described in United States Patent No. 760,732. 65

The shuttle is mounted within the head 5 and may be constructed as shown in the Patent No. 760,732 referred to.

The loop take-off and the spreader (not shown) which may be of the construction 70 shown in Patent No. 760,732 are mounted in the bracket 5. Both are operated by mechanism mounted on the head 1.

The awl bar 33 carrying an awl 34, and having a cross head 35 is guided in the 75 bracket 4 and carries a block 37 engaging a fork 38 on an arm 39 fixed to a rock shaft 22, and having an arm 40 provided with a cam roll engaging a cam groove in the left face, Figure 3, of the cam wheel 9. 80

The presser-foot 41 is mounted on a bar 42, carrying a cross head 43 movable along a guide 44, and pressed downwardly by a leaf-spring 45 pivoted at 46 on the bracket 47, having a yoke 48 provided with a screw 85 49 bearing on the leaf-spring to tension the same. In order to raise the presser-foot manually, pivoted at 50 on the machine head, is an arm 51, the toe 52 of which engages an adjustable screw 53 on the cross 90 head 43. The arm 51 is provided with an aperture 54 adapted to receive a rod or wire leading to a treadle (not shown).

The presser-foot may be operated substantially as shown in Patent No. 760,732. 95

The looper may be constructed and operated as shown in Patent No. 760,732.

The thread cop 83 is mounted on the machine head, and the thread passes between pairs of thread tensioning discs 85 to the 100 wax-pot 86. The thread passes from the wax-pot through an apertured lug 96 through an eye in the outer end of an auxiliary take-up lever 97, which is acted upon by a spring 98. From this auxiliary take-up lever, the thread passes through trucks on a pair of take-up arms 100 and 101. The take-up arm 100 is fixed to the rock shaft 102

and this take-up arm is also connected by a link 103 to the arm 104 on the take-up arm 101, thereby these take-up arms will be operated in unison.

5 The heat is in this particular embodiment supplied by gas, the main gas pipe being shown at 120 (Figure 3) and this gas pipe is jointed to a chest or distributor 121 from which lead pipes 122, 123, 124 and 125, these 10 pipes being respectively controlled by valves 126, 127, 128 and 129. The pipe 122 leads to and opens adjacent the wax-pot 86, this wax-pot being spaced from the side face of the machine head, and the pipe 122 opening 15 at 130 thereby providing a combustion space for the flame. The pipe 123 opens at 135 opposite a flange or extension 132 on the take-up lever 101 and this flange is also spaced from the side face of the machine 20 head so as to furnish a combustion space. Similarly, the pipe 124 opens at 133 contiguous a flange or ear 134 on the take-up lever 100, which flange or ear is spaced from the side face of the machine head so as to 25 furnish a combustion space for the flame. The flanges or ears 132 and 134 are provided to furnish heating surfaces impinged upon by the flames from the openings 135 and 133. The pipe 125 opens at 131 underneath the shield or hood 136 so as to direct 30 the heat to the shuttle mechanism.

It will, therefore, be seen that with this 35 construction the heating system distributes the gas to the different parts of the devices which handle the wax thread, and that the distribution of the gas may be accurately controlled by the manipulation of the valves. It will, of course, be understood that these 40 valves are ordinary needle valves which control the passage of the gas from the chest 121 to the different pipes, and in order to keep these valves in any desired position of adjustment, each valve has a spring 137 arranged between its head and the cap 138 45 on the steam chest.

It is not necessary to describe in detail 50 the sequence in operation of the several parts, since the general sequence in opera-

tion is substantially the same as in the patent referred to, to which reference is had. 50 In the general operation, the elements perform their respective functions in the same manner and in the same sequence as in the patent referred to, although in details of construction and in details of operation, 55 some of the mechanisms are different, and improved from the corresponding mechanisms of the patents.

It is obvious that various changes may 60 be made in details of construction without departing from the spirit of this invention; it is, therefore, to be noted that this invention is not to be limited to the specific construction shown and described.

Having thus described the invention, 65 what is claimed is:

1. In a wax thread sewing machine having a frame and thread handling devices thereon, a heating system, comprising, heating jets for said devices, a gas chest accessibly located on said frame and having a gas connection, gas pipes leading from said chest to said several jets, and valves on said chest adapted to independently control at the chest the admission of gas from said 75 chest to said pipes.

2. In a wax thread sewing machine, having a base, and thread handling devices thereon, a heating system, comprising, heating jets for and adjacent said devices, a 80 gas chest arranged along said base and having a gas connection, gas pipes leading from said chest to said jets, and valves on said chest adapted to independently control at the chest the admission of gas from said 85 chest to said pipes.

3. In a wax thread sewing machine, a moving take-up element having an extension adapted to provide a flame receiver, and a stationary burner, adapted to direct 90 a flame on said extension throughout its movement, in order to heat said take-up.

In testimony whereof I affix my signature this 25th day of May, 1918.

STEPHEN A. DOBYNE.
